SWIMMING POOL CLEANER

Howard M. Arneson, 439 Dubois St., San Rafael, Calif.

Filed July 23, 1965, Ser. No. 86,266

Term of patent 14 years

(Cl. D9—2)

FIG. 1

FIG. 2

FIG. 3

FIG. 4

FIG. 1 is a top plan view of a swimming pool cleaner, showing my new design.

FIG. 2 is a back elevational view thereof.

FIG. 3 is a side elevational view thereof.

FIG. 4 is a bottom plan view thereof.

The dominant features of my design reside in the portions shown in full lines.

I claim:

The ornamental design for a swimming pool cleaner, as shown and described.
